UNITED STATES PATENT OFFICE.

ASA L. PARRISH, OF ELKHART, INDIANA.

PAPER-BAG MACHINE.

974,704.

Specification of Letters Patent. Patented Nov. 1, 1910.

Application filed July 19, 1909. Serial No. 508,381.

To all whom it may concern:

Be it known that I, ASA L. PARRISH, a citizen of the United States, residing in the city and county of Elkhart, in the State of Indiana, have invented certain new and useful Improvements in Paper-Bag Machines, of which the following is a specification.

My invention relates to machinery for manufacturing satchel-bottom bags from 10 bellows tucked tubing.

The objects of my improvements are to provide a bed or base that will be rigid and convenient, upon which the bag machine and attendant mechanisms may be assembled; 15 to provide mechanism for cutting, creasing and opening the bellows sided tubing in such manner as to facilitate the spreading of the end of the bellows tubing into the diamond form; and, for the purpose of spreading out 20 the end of the tubing into the diamond form, to provide mechanism that will be comparatively simple, easily adjusted, and readily understood.

The improvements will be best understood 25 by referring to the drawings forming a part of this specification, in which—

Figure 1 is a side view of the bag machine in which unnecessary details are not shown; Fig. 2, a top view of the base of the machine, 30 the mechanisms which it supports being removed; Fig. 3, a side view of a top cutting device; Fig. 4, another view of the mechanism shown in Fig. 3, looking in the direction of arrow at Fig. 3; Figs. 5 and 6 are 35 enlarged details of Fig. 3; Fig. 7, a view of a creasing device taken on line T. T. of Fig. 14, all gearing being omitted; Fig. 8, a creasing plate and tuck opener; Fig. 9, a detail of Fig. 8, showing a section taken on line n n 40 of Fig. 8; Figs. 10 to 12 show operations being performed; Fig. 13, a fragment of tubing showing the effect of the performed operations; Fig. 14, a side view of the mechanism shown in Fig. 7, also parts of the diamond fold forming, and main cutting mechanisms, the near side frame being omitted 45 for clearness; Fig. 15, a detail of the mechanism shown in Fig. 16; Fig. 16, an enlarged view of the diamond fold forming mechanisms taken on line V. V. of Fig. 14; Figs. 50 17 to 22, are details of the bottom forming and side gripping devices, and show some of their operations; Figs. 23 and 24, show the diamond of the bag bottom in an advanced 55 position, the side gripping and cutting devices being omitted; Figs. 25 and 26, are de-

tails of the main cutting device; Figs. 27, 28 and 29, are further explanatory details of the side gripping devices; Fig. 30, a detail of a final pasting and cutting device; 60 Figs. 31 to 34 show operations performed upon the paper by this machine.

Similar letters and figures refer to similar parts throughout the several views.

All parts of this machine are secured to 65 other parts where necessary, by bolts, screws and means common in shop practice, and are not shown in these drawings where not necessary.

Referring to Fig. 1, A indicates a base or 70 bed upon which the parts of the bag machine are assembled and secured where necessary in any usual manner; the base A is constructed with a flat top, having sides and ends at substantially right angles with 75 the top face, making a base that is hollow underneath, and giving it somewhat the shape of a large hood or cover; in the hollow space in the under side of the base are located stiffening ribs a^1 , in any convenient 80 position; a^2 indicates an opening in the base which has sides and ends a^3 , extending downward from the top about the same distance as the outer sides. The slightly raised faces a^4 , on the top of the base and its sides, 85 are finishing faces upon which different parts of the bag machine are secured; a^5 are legs which support the body of the base, clear of the floor. This base, consisting of 90 the parts substantially as indicated, is cast 95 integral, making a very rigid and substantial base which is not liable to spring or twist, and will hold the different mechanisms supported by it in correct alignment. A depression, a^7 , is formed in one side of the 95 base, (best seen in Fig. 2,) by locating a part of the side wall nearer to the center line I, I, of the base. It is also obvious that the side frames such as are found in most machines, over and around which the operator 100 must lean while working, are not found in this section of this machine, their absence and the depression a^7 allowing the operator to stand in a nearer and more convenient position to the machine while performing necessary operations in connection with this 105 section of it. a^8 indicates a device for pressing the folded and pasted bags; the device may be of any convenient form, and mounted upon the base A. The carrier belt and 110 its rolls a^{10} , for removing the folded bags from the machine, are supported within the

opening a^2 , and below the top of the base, which allows the bag machine mechanisms to be located conveniently lower than would be the case if the carrier belt and its rolls were located on top of the base. A motor a^3 , 5 may be mounted upon the base and furnish the power with which to operate the bag machine and its attendant mechanisms.

The former post b^1 , Fig. 3, is secured to 10 the base A, and has secured to its upper end a part of a tucked tube forming device b , the thin plate b^3 , of the former extending somewhat to the rear of the post b^1 , and having the usual downward bend, over 15 which the paper P is drawn, the downward bent end of the plate being secured to brackets 12, and having an opening b^4 , cut through it, in which the periphery of roll 10 is located, the roll being supported to rotate in bearings 11 of brackets 12, which are secured to post b^1 . The roll 10, (Figs. 5 and 6,) has turned in its face two grooves 13, 13, and the groove 14 cut in the face of the roll at right angles with, and having 25 rounded ends where it joins the grooves 13, 13, which are cut clear around the roll to save shop time. A portion of the face of roll 10 is cut away between the grooves 13, 13, Fig. 5, or clear across the face as shown 30 in Fig. 6, in such manner as to leave a corner or creasing edge 15. The block 16 has a socket 17 formed in it, and secured in the socket are a tab cutting knife 18, and a creasing blade 19; the knife 18 is formed so 35 as to match the combined shape of the grooves 13, 13, and 14. The block 16 is secured to shaft 20, which revolves in bearings 21 and 22, which are secured by their flanges 21^c and 22^c, to upright bracket 23, the hubs 40 of bearings 21 and 22 extending into slotted openings 23^a and 23^b, the slotted openings being for the purpose of permitting adjustment of the different mechanisms toward or from each other as may be desired, and also 45 permitting the use of gears and cutting devices of different diameters, with the same bracket...

The bracket 23 is secured to the base A, and has secured to it bearing 24, in which 50 is supported one end of shaft 25, which obtains its motion from shaft 1, Fig. 1, through a pair of miter gears 25^a and 25^b; gear 26 is secured to shaft 25, and meshes with miter gear 27 secured on shaft 20, 55 which revolves in the same direction as the paper travels; gear 28 is secured to shaft 20, and meshes into gear 29, secured to pin 30, revolving in bearing 31, which is secured to bracket 23 by its flange 31^a; gear 29 meshes 60 with gear 32, secured to shaft 33, which is supported in bearings 34 and 35, bearing 34 being secured by its flange 34^a to bracket 23, and bearing 35 being secured to former post 65 b^1 ; gear 36 is secured to shaft 33, and meshes with gear 34^c which is secured to roll 10 in any

convenient manner. The circumference of roll 10 is equal in length to the length of the bag tube desired, and block 16 is turned to the same radius as roll 10, and when motion is applied to them through the gears as 70 described, they will revolve in time with each other, and the paper P, passing over the former plate b^3 , and between the block 16 and roll 10, will have the tab p^2 cut in it by knife 18, the teeth of which will pass 75 through the paper and extend into the grooves 13, 13, and 14, in roll 10, and the creasing blade 19 will crease the tab just back of the creasing edge 15, and cause the tab to stand at an angle with the paper, for 80 purposes later explained.

The side frames 3, 3, (Figs. 7 and 14,) support the bearings 37, 37, in which is journaled shaft 38, having secured to it two creaser hubs 39, 39, and above bearings 37, 37, are separators 40, 40, upon which rest bearings 41, 41, having journaled in them shaft 42, to which is secured two creaser hubs 39, 39. The creaser hubs 39, which are all alike, have extensions 43, on one side 85 of them, and each extension has a creaser blade 44, at its end. The shafts 38 and 42 revolve in time with each other, and cause the creaser blades 44 to come in contact with the tucked tubing once for every bag 90 length, at a position where the corners of the bag bottom are to be formed. All of the bearings and separators in this section of the machine are held securely in place by frames 3, 3, by screws 50, 50, threaded in 100 straps 3^c 3^c, or other convenient means. Bearings 41, 41, have, made integral with them, sleeve extensions 44, 44, upon which are secured collars 45, 45, which being constructed substantially alike, the explanation 105 of one of them will be deemed sufficient. Collar 45, has formed integral with it, an extension 46, which has a further right angle extension 46^a at its outer end extending toward the center of the bag machine; the 110 side face 46^b is cut away near its outer end, forming faces 46^c, 46^d, and secured to face 46^b, is an angle shaped piece 47, thereby creating a right angle slot or slideway, in 115 which is supported, to slide freely, an angular shaped piece 48. The angular shaped piece 49, (Fig. 8) has formed on one of its sides, an extension 51, which may be of any convenient shape, here shown somewhat pointed, and having creasing grooves 51^a 120 formed in its top and bottom faces, (Fig. 9) and its edges are preferably beveled. A pin 51^b, is secured to the upright side of angle 49, upon which, roll 51^c is loosely supported. Loosely supported in side frames 3, 3, is 125 shaft 52, upon which are secured levers 53 and 53^c; lever 53 has secured to it a pin 53^a, upon which is loosely supported cam roll 53^b bearing against the face of cam 56, which is secured to shaft 38. The spring 57 sup- 130

ported on shaft 52, and having one of its ends 57^a secured to side frame 3, exerts a pressure at its other end 57^b, upon lever 53, in a direction which compels roll 53^b to bear against cam 56 at all times. Both levers 53 and 53', have U shaped ends 58, 58, in which the rolls 51^c are located. A short slot 59, is formed in the side wall of angle 47, which provides clearance for the roll 51^c when it is at its extreme forward position.

The tubing P' when passing shafts 38 and 42, straddles its side, tucks over the extensions 51, of the angles 49, or, for a better understanding, I will say, the proper place for the extensions 51, during the operation of the machine, is within the tucks of the tubing P'. The cam 56 is so shaped as to cause the free ends of levers 53 and 53' to oscillate back and forth, and they through contact with rolls 51^c, cause the angles 49 to slide back and forth in the slideways, and as the creaser blades 61 come in contact with the tubing P', the angles 49 are caused to meet and travel with the blades 61 so that the creasing grooves 51^a will be in line with the blades 61, and as the tubing P' travels with the creasing devices during their combined operation, it will be creased substantially as shown in Fig. 13, that is, one face of the tubing, and one-half of the tucks will be creased in one direction, and the opposite face of the tubing and its half of the tucks, will be creased in the opposite direction. As shown in Fig. 7, one side of the tubing and tucks will be creased up, and the opposite side of the tubing and tucks will be creased down, and all of the creases will extend from the outside edges of the tubing toward the center, a distance approximately the depth of the tucks. It will be seen by the foregoing explanation that one function performed by angles 49, and their extensions 51, is that of angular creasing plates, and an explanation of their operation is best shown and illustrated in Figs. 10 to 12, in which the tuck of the tubing is cut away for a clearer view. After the creasing blades 61 have revolved out of contact with the tubing, the angles 49 cease to travel in a direction with the paper, and are caused, by cam 56, and levers 53, 53', to slide in a reverse direction, to the position shown in Fig. 10, meeting and traveling in time with the creaser blades as set forth.

The extensions 51, also perform the very important operation of separating, or opening the tucks of the tubing, so that the side gripping devices of the bottom forming portion of this machine may enter the tucks readily.

Supported in frames 3, 3, are bearings 65 and 66, in which are journaled shafts 63 and 64, upon which are secured rolls 67 and 68, situated a distance apart and carrying a cutting mechanism, Figs. 25 and 26. Roll

67 has a clearance space 69, formed in one side of it, and secured to one wall of the clearance space is a cutting blade 70, a portion of which, 70^a, is cut away leaving a clear space in its center. A backing strip 72 is carried by roll 68, which backs up the tubing P', while the knife operates upon it, and has a clearance space 73, formed through its length to clear the points of the knife teeth as they cut through the tubing P'. It also has a portion 72^a cut away so as to be clear of the paper and avoid straining it at this central point when the sides of the tubing are being cut by knife 70. A gripping bar 74 is carried by roll 67, having pins 75 formed upon it, which are loosely inserted into holes 76 in roll 67, pins 78 being secured in pins 75, the ends of pins 78 projecting into holes 80 in roll 67, thereby retaining gripping bar 74 to roll 67 during its rotation, the holes 80 being larger than pins 78 permit the bar 74 to move to and from the roll 67, which enables the bar 74 to grip different thicknesses of tubing between its face and the backing strip 72, the bar 74 being held against the tubing P' by springs 81, inserted in holes 82, in rolls 67, thereby holding the tubing tightly, so that the teeth of knife 70 will cut through it readily, and not push the tubing into the clearance space 73 of backing strip 72. By referring to Fig. 32, it will be seen that the tucked tubing P', is cut on the line p¹, which is back of the cross line p⁸' of the thumbplace p⁸, and if the tab p² lay down in the opening from which it is cut, the knife 70 would cut into and mutilate it, and to prevent such mutilation is one of the objects which I accomplish by creasing the tab p², and thus cause it to stand away at an angle to the face of the tubing P', and the knife 70, as it is rotated, will pass the creased or bent back tab p², leaving it uninjured and projecting into the clearance space 69, of roll 67, the teeth of knife 70, as it rotates further, cutting through all of the plies of the tubing P', leaving a narrow uncut portion p¹⁰, in the center of the bottom ply.

Secured to and rotating with shafts 63 and 64, are collars 83, which, being all alike, explanation of one will be sufficient. In Fig. 22, collar 83 has extension 84 formed integral with it, and secured to the extension 84, is a piece of cushioning material 85, and it is also supplied with spring holding means 83^a. The collar has bearing faces 86 on each side of it, Fig. 20, against which shoulder screws 87 are secured, and supported upon the screws 87, is a side gripper 88, of special design.

The side gripper 88 is made of metal, preferably of steel, and in one piece, Fig. 21, and while I may be obliged to designate the different features of this gripper by different names, which I do for the purpose 130

of explanation only, I consider it one piece of mechanism, and I shall refer to it as a side gripper, or, gripper 88, as may seem suitable.

5 The gripper 88 can be of any convenient shape, being shown in these drawings somewhat flat shaped, having on its free end a bearing or contact face 89, and a gripping extension 90 located near one end of contact 10 face 89. The inner end of the side gripper is formed so as to leave a leg extension 91, at each side, the legs being straddled over collar 83; and the side gripper being loosely supported upon shoulder screws 87, which 15 are inserted through holes 92, in legs 91, and secured to collar 83. One end of spring 93, is secured to the side gripper through holes S, and the other end is secured to any convenient means, as pin 83^a. The collar 20 83, and side gripper 88, are secured in position upon shaft 64, with roll 68, (Fig. 27), or equivalent means, and the side gripper is held securely in an inclined position toward roll 68, by any means, the gripping 25 extension 90 resting against the face of roll 68, and while the side gripper is held in this inclined position, the contact face 89 is turned to a radius that is equal to the distance from the center of shaft 64, to a center line L, between rolls 67 and 68, and after 30 the turning of face 89 has been completed, the holding means may be dispensed with, to permit the side gripper to swing freely upon supporting screws 87. By referring 35 to Fig. 19, it will be seen that if but one side gripper was left in place upon its shaft, and the other one was removed, the one remaining in position would rotate with its shaft indefinitely without any movement toward 40 the accompanying roll or the tubing, on account of the total absence of cams, rolls or other mechanisms, such as are generally used in the operation of side grippers in most bag machines. To obtain the desired 45 movement, I have designed these side grippers to operate in pairs, and a better understanding of their operation will be had from the following explanation:

Secured to shaft 63, Fig. 28, is a collar 50 83, and a side gripper 88, which are constructed the same as the ones on shaft 64, and previously described; when the free ends of grippers 88 are swung backward from rolls 67 and 68, the contact faces 89 55 extend beyond the center line L, in which case, if they are rotated, they will come in contact as they approach each other in coming to the position where they grip the tucked tubing, and, after further explanation 60 it will be obvious that I intend them to come in contact. To prevent the side grippers from coming together harshly, I relieve the forward or contacting ends 96 of contact faces 89, so that the ends 96 will be 65 on about the radius of the center line L,

when the side grippers are in their swung backward position. The broken line r in Fig. 20, show the greater radius occupied by faces 89; when grippers 88 are in the backward position shown in Fig. 28, the radius 70 of the contacting ends is gradually increased from the ends 96, until the full radius of the faces 89 is met, at about the point 97; the contacting ends are also given a somewhat rounded shape as shown at 98, 98, 75 Fig. 29, and if desired, the whole length of the contact faces 89 may be given the same, or a somewhat similar shape; the contact faces 89 being relieved at the ends 96 will permit the grippers 88 to come together 80 gently as they rotate.

When the side grippers are in their backward position, Fig. 28, the contacting ends 96 are on a line with each other that is a distance inside of the center line through 85 supporting screws 87, as indicated by broken lines y, y, x, x. It is obvious that the springs 93 pull the free ends of the side grippers and cause them to swing backward from the rolls 67 and 68, and hold them against the cushions 85 when they are out of contact with each other, best seen in Fig. 19. As the side grippers continue to rotate after contacting at ends 96, they will push increasingly against each other as they roll against the increasing 90 radii of the contacting faces from ends 96 to positions 97, and as the points of contact at 96 are inside of the supporting screws 87, the free ends of the side grippers, as they push increasingly against each other, 100 will also push or swing each other inward toward their accompanying rolls, the rounded faces 98 permitting them to roll against each other easily, and the gripping extensions 90 will be projected into the tucks of 105 the tubing P', and grip the tubing to the rolls 67 and 68, at points where the creases P^a, P^b, have previously been made, and where the corners of the bag bottom are to be formed, the springs 93 lengthening out 110 as the grippers 88 swing each other inward.

The side grippers continuing to rotate and bear against each other's faces 89, will continue to grip the tubing to the rolls 67 115 and 68, forming the corners of the bag bottom and drawing the creases P^a, P^b, of the tucks into a straight line, reaching the position shown in Figs. 17 and 18, when they will begin to gradually run out of contact with each other at a point 99, from which point to their ends the faces 89 are relieved in substantially the same manner as at their leading ends 96, and as they run out of contact the springs 93 pull the grippers 120 away from the partly formed bag bottom, and back against the cushions 85, Fig. 19.

The contact faces 89 could be terminated at the point 99, which would permit the grippers to be pulled back against the cush- 130

ions very quickly and harshly, which would be objectionable, the gradual releasing from contact being preferred. It is obvious that the cushions 85 are for the purpose of preventing the grippers 88 from striking against the extensions 84, the striking of which under high speed, would make noise and batter the striking parts out of shape. Referring to Fig. 16, it will be seen that there are four side grippers 88 with their attendant parts, one pair at each end of rolls 67 and 68, and secured to shafts 63 and 64, and rotating therewith. When a change of paper is made during the operation of the machine, from a heavy sheet to a lighter one, the side grippers will not grip the paper to the rolls firmly, which will cause the making of bad shaped bags, and to overcome this difficulty I have provided the following explained adjustment, which is to compensate for the different thicknesses of paper operated on, and is consequently very slight. Bearings 65, 65, of shaft 63, and supported in frames 3, 3, Figs. 15 and 16, are arranged for an up and down movement produced by turning the screws 101 threaded in straps 3' 3', and are held against the screws 101 by springs 102. It will be seen that by turning the screws 101 downward the side grippers will be pushed together and their free ends will swing farther in toward their accompanying rolls, and the extensions 90 will grip the paper more securely. The reverse operation from the foregoing being the case when a change is made from a light sheet to a heavy one. In Fig. 17, a side gripper has a portion of it cut away showing a blade 100 secured to roll 67, during the rotation of which, and the time of forming the corners of the bag bottom, the upper face of the tubing P' is bent over the blade, defining the crossline p¹², on which the bag bottom is folded when flattened into the diamond form.

Secured upon straps 3' 3'; and to frames 3, 3, by screws 103 are extensions 104 supporting cross-bar 105, near the center of which is secured by screws 106, a plate 107, having its secured end formed at an angle with the main portion, the free end of which is curved and may terminate in a straight end 108 or the curved shape may extend to the extreme end. Formed upon the face of the plate is a stiffening rib 109 supporting diamond fold flattener 110, which with the rib 109 and plate 107 are cast integral, Figs. 14 and 16. The plate 107 has two clearance spaces 111, formed in its edges to clear the inner creases of the side tucks of the tubing P' as it moves forward. The tab p² standing at an angle with the tubing, will come in contact with the back face of plate 107 and slide upward as the side grippers open the end of the tubing to the shape shown in Figs. 17 and 18, which is substan-

tially what is known as the box form the up-standing position of the tab at this time facilitating its movement upward along the back face of said plate 107 and preventing its becoming mutilated or turned in a wrong direction. During the operation of opening out a tucked tube and spreading a diamond form on the end of it, the difficulty encountered in folding the sides p⁶, p⁶, in an inward direction is well known, and complicated and expensive operative mechanism is necessary in most bag machines to overcome the difficulty. I overcome the difficulty largely by forming the creases p⁸, p⁸, in the tubing P', reference being had to Figs. 17 and 18, in which but one-half of the bottom forming mechanisms are shown, they being deemed sufficient for explanation. When the side tucks of the tubing are spread apart by the grippers 88, the creases p³, p³, will be drawn into a straight line with each other, forming substantially one crease on the line where the side edge of the bag bottom is to be formed, giving them the appearance of having been creased from the inside of the tubing toward the outside, and as paper generally folds in a direction opposite to the direction in which it is creased, the sides of the bag bottom p⁶ will be inclined inwardly and will fold into the desired diamond form very readily and without the use of much mechanism. As the side grippers release their hold upon the corners p⁴, p⁴, the box form of the bag bottom is drawn forward and downward by the connection p¹⁰ with the preceding bag body and rolls 112, over table 4 secured to frames 3, 3, the plate 107 retarding the upper or rear portion at tab p², which elongates the bag bottom, Fig. 19, and induces the sides p⁶ to fold inward and over the face of plate 107, and as the bag bottom still further progresses, Figs. 23 and 24, the rear end of the bag bottom is drawn along against plate 107, being gradually inclined backward, folded on the crossline p¹² and against the body of the tubing. In the meantime the sides p⁶ of the bag bottom contact with and pass under the ends of flattener 110, by which the sides p⁶ are flattened into the diamond form, the diamond being pressed and pasted in any usual manner as it passes between rolls 112, the connection p¹⁰ being severed by the knife 113 as it passes between rolls 114. The well known final folds p¹⁴ and p¹⁵ are then made by any well known means, closing the bag and completing it by the usual pressing. By the foregoing explanation it will be seen that the mechanisms used in the diamond fold forming section of this machine are few in number and very simple, with very slight and readily understood adjustments, the multiplicity of mechanisms found necessary in this section of other machines of this class being conspicuously absent.

sent from this one; as for instance, the ones shown in Patents No. 578,550 granted to C. E. Dulen; and No. 736,673 granted to P. L. Bartholomew.

Any convenient means may be employed to supply motion to this bag machine, as from motor a^9 , to gear g^2 secured to shaft 1, or by a belt on pulley 2, secured to shaft 1, in place of gear g^2 . Shaft 1 being the main driving shaft has secured to it miter gear 25^g meshing with miter gear 25^{g'} secured to shaft 25, to which is secured miter gear 26 giving motion to miter gear 27 on shaft 20 as before set forth, and through it to the tab cutting mechanism.

Referring to Fig. 1, secured to shaft 1 is gear g^3 , and moves gear g^4 secured to shaft 38; gear g^4 moves gear g^5 secured to shaft 42, and gear g^5 conveys motion through 20 loose pinion g^6 to gear g^7 on shaft 63. Gear g^4 also gives motion through loose pinion g^8 to gear g^9 secured to shaft D^1 , and gear g^9 moves gear g^{10} on shaft D^2 . Gear g^9 also gives motion to gear g^{11} secured to shaft 64, 25 and gear g^{11} through loose gear g^{12} to gear g^{13} on shaft 115; gear g^{13} moves gear g^{14} secured to shaft 116, and it to gear P^P , which rotates paste roll C. Gear g^{13} also gives motion through loose pinion g^{15} to gear g^{16} 30 secured to shaft 117, gear g^{16} moves loose gear g^{17} , and it moves gear g^{18} secured to shaft 118, upon which is secured roll a^{10} , which transmits motion through carrier belt 119 to presser a^8 and its attendant mechanisms. Gear g^{19} secured to shaft 120 receives motion from loose pinion g^{15} , and gives motion to gears g^{20} , g^{21} and g^{22} , secured to shafts 121, 122 and 123. All loose gears and pinions are supported upon suitable 40 pins which are secured in proper positions for the gears and pinions to operate. It is obvious that when motion is applied to shaft 1, all gears and their attendant mechanisms in this machine will rotate in the proper direction and in time with each other as desired.

Fig. 31 indicates paper being formed into tucked tubing, with tabs p^2 cut in it and standing at an angle with the paper. Fig. 50 32 is a continuation of Fig. 31, showing the creases p^3 , p^4 , made in the tubing at a position where the corners of the bag bottom are to be formed, and at an advanced position showing the tubing cut through all of its 55 plies leaving a narrow uncut connection P^{10} , and the tab p^2 unmutilated, and at a further advanced position showing the end of the tubing thrown into substantially the box form, the top face of the tubing having been 60 bent in the meantime over the edge of a blade on the line P^{12} . Fig. 33 shows the bag bottom flattened into the diamond form against the tubing, having paste P^{13} applied in a usual manner, the connection P^{10} severed, and at a still further advanced position

the first final fold P^{14} of the bag bottom. Fig. 34 shows the last final fold P^{15} having been made, closing the bag bottom, after which it is finished by pressing.

The operation of the machine is as follows:—The paper is drawn into the machine by the usual draw rolls upon shafts D^1 and D^2 , becoming tucked tubing as it is drawn over the former b . The tabs p^2 are cut in the paper by knife 18, and creased by 70 creaser blade 19 just back of the creasing edge 15 upon roll 10, causing the tabs to stand at angle with the paper as it is drawn between roll 10 and block 16 and into the machine. As the shafts 38 and 42 rotate, 75 the cam 56 oscillates the levers 53 and 53', causing the creasing plates within the tucks of the tubing to meet and travel with the creasing blades 61 as they rotate, and crease the tubing as it travels with them, at points 80 where the corners and side edges of the bag bottom are to be formed, the creasing blades 61 continuing in their rotation and the cam 56 causing the levers 53 and 53' to oscillate and move the creasing plates backward to 85 meet the next oncoming bag position in the tubing. As the tubing moves forward the knife 70 passes the tab p^2 which projects into the clear space 69, the tubing is gripped by the bar 74 against backing strip 72 while 90 the knife 70 cuts the tubing, leaving a narrow uncut connection p^{10} in the bottom side, the creasing plates within the tucks of the tubing being also separators, will cause the tucks to open apart after the tubing is cut 95 by knife 70. Shortly after the tubing is cut and the tucks are separated, the side grippers come in contact with each other as set forth, and swing their extensions 90 into the tucks of the tubing and grip it to rolls 100 105 67 and 68, at points where the corners of the bag bottom are to be formed, and where the creases p^3 , p^4 , have been made, the grippers holding the tubing to the rolls as they rotate to the position shown in Figs. 17 and 18, 110 which is substantially the box form, in the meantime the tab p^2 contacting with plate 107 and sliding upward and the top face of the tubing being bent over blade 100. At 115 this position the side grippers begin to run out of contact, releasing the corners of the partly formed bag bottom and being pulled back by springs 93 against cushions 85. As the side grippers release the corners p^4 , p^4 , the box form of the bottom is drawn forward and downward by the connection p^{10} 120 and rolls 112 over table 4, and as it is drawn along the plate 107 retards the rear portion of tab p^2 , elongating the bag bottom and causing the sides p^6 to fold inward and over the face of plate 107, which inclines the rear end of the bag bottom backward, 125 folding it on the crossline p^{12} and against the body of the tubing, the sides p^6 being flattened into the diamond form by flat- 130

tener 110, after which the bag bottom is pressed, pasted, severed at p^{10} , and the final folds p^{14} and p^{15} are made and pressed in a manner as set forth.

- 5 The tubing, when cut through all of its plies and still being connected with the preceding bag at p^{10} , is considered as having an end upon it and is referred to as such in this specification. The direction in which 10 the paper travels in this machine is considered the forward one.

I have shown the side grippers in this machine as operating in connection with a pair of rolls carrying other mechanisms, 15 which is not absolutely necessary, as the side grippers may be operated with a pair of plain rolls and the other mechanisms operated in any other desired position or manner, in fact the side grippers may be used 20 in other machines and coöperate with mechanisms that are entirely different in their construction and operation from the ones herein shown, and still perform the operations for which I have designed them.

- 25 I have designed the creasing mechanisms for forming the creases P^2 P^3 more particularly for use in connection with heavy weight papers that are stiff and difficult to fold, and they may be dispensed with 30 when the machine is handling paper of lighter weight. And I wish it to be understood that variations from the mechanisms herein specified can be made without departing from the spirit of my invention.

35 The tucked tube forming, pasting, pressing, final severing and folding devices of this machine are, or may be, of any well known type, and the details of such devices are shown only so far as is deemed necessary 40 for a complete understanding in connection with the devices which more particularly pertain to this invention.

What I do believe to be new, and desire to secure by Letters Patent is—

- 45 1. In a paper bag machine, the combination of rolls between which tucked tubing passes, rotating side grippers as 88, 88, 88, 88, arranged to enter the tucks of the tubing and having bearing faces opposing each other and extensions adapted to grip 50 the paper to the rolls, said rolls carrying a tube cutting mechanism, and one of said rolls having a clearance space formed in one side of it.

55 2. In a paper bag machine, the combination of rolls between which tucked tubing passes, rotating side grippers as 88, 88, 88, 88, arranged to enter the tucks of the tubing and having bearing faces opposing each other and extensions adapted to grip the paper to the rolls, said rolls carrying a tube gripping and cutting mechanism, and one of said rolls having a clearance space formed in one side of it.

- 65 3. In a paper bag machine, the combina-

tion of a pair of rolls between which the tubing passes, side grippers as 88, 88, 88, 88, arranged to enter the tucks of the tubing and having bearing faces opposing each other and extensions adapted to grip the paper to the rolls; and a blade carried by one of the rolls upon which one face and its tucks only of the tubing are bent defining the crossline P^{12} .

4. In a paper bag machine, the combination of a pair of side grippers suitably supported for rotation, with means against which to grip tucked tubing, bearing faces upon the outer or free ends of said grippers adapted to bear upon one another, whereby 80 they act to grip said tubing against said means, and the inner ends of said grippers being adapted for their support.

5. In a paper bag machine, the combination of a pair of side grippers suitably supported for rotation, with means against which to grip tucked tubing, means for gripping the tubing, bearing faces upon the outer or free ends of said grippers adapted to bear upon one another whereby they act 90 to project their gripping means within the tucks of the tubing and grip it against said means, and the inner ends of said grippers being adapted for their support.

6. In a paper bag machine, the combination of a pair of side grippers suitably supported for rotation, with means against which to grip tucked tubing, gripping extensions located near one end of bearing faces located upon the outer ends of the 100 grippers, said bearing faces being adapted to come in contact whereby they act to grip the tubing to said means, said bearing faces being formed to a suitable radius and having their ends relieved, and the inner ends 105 of the grippers being adapted for their support.

7. In a paper bag machine, the combination of a pair of suitably supported rotating side grippers, with means against which to 110 grip tucked tubing, bearing faces and gripping means located upon their outer or free ends, their inner ends being adapted for their support, the bearing faces being formed to a suitable radius and given a 115 rounded shape, and the ends of the bearing faces being relieved, and means to rotate the grippers.

8. In a paper bag machine, the combination of a pair of side grippers suitably supported for rotation, with means against which to grip tucked tubing, gripping extensions 90, bearing faces 89 with relieved and rounded ends, leg extensions 91, holes 92, and spring securing means, all substantially as specified.

9. In a paper bag machine, a pair of parallel shafts, collars fast upon said shafts, rotating side grippers loosely attached to said collars and having bearing faces adapted to 130

be brought into contact, cushions secured to the collars and means arranged to pull the grippers against the cushions.

10. In a paper bag machine, the combination of a pair of rotating side grippers, suitable supports therefor, and means for rotating the grippers, said grippers having opposed bearing faces on their outer ends arranged to come in contact with and bear against each other, whereby the grippers are caused to project their gripping ends into the tucks of the tucked tubing.

11. Means in a paper bag machine for the manipulation of different thicknesses of paper by side grippers, comprising, a pair of shafts, a pair of rolls secured to the shafts, side grippers arranged in pairs at each end of the rolls, means to support and rotate the shafts, rolls and grippers, said grippers bearing against each other as they rotate, thereby projecting their gripping means near to said rolls to grip the paper to the rolls and means for varying the distance between the grippers whereby they may operate on different thicknesses of paper.

12. In a paper bag machine, mechanism for opening out the box form on the end of tucked tubing consisting of a pair of rolls between which the tubing passes in combination with four rotating side grippers arranged to operate in pairs and having opposing bearing faces adapted to be brought into contact whereby the grippers grip the tubing to the faces of the rolls and open out its end into the box form of the bag bottom to be formed, and a blade, carried by one of the rolls, upon the edge of which one face of the tubing is bent while the box form is being opened.

13. In a paper bag machine, the combination of a pair of rolls between which the tubing passes, four side grippers as 88, 88, 88, 88, arranged and attached to the shafts in pairs at each end of the rolls and rotating therewith, the grippers of each pair being adapted to contact with each other and thereby themselves to project their gripping ends between the rolls and the tucks of the tubing, and to grip the tubing to the face of the rolls and spread open the end of the tubing into substantially the box form of the bag bottom, the grippers also releasing their grip upon the tubing and means to retract the grippers from the tubing as they release it.

14. In a paper bag machine, the combination of a pair of rolls between which the tubing passes, side grippers as 88, 88, 88, 88, arranged to operate in pairs and attached to the shafts at each end of the rolls and rotating therewith, the grippers of each pair being adapted to contact with each other and thereby themselves to project their gripping ends between the rolls and the tucks of the tubing, and to grip the tubing to the face of the rolls and spread open the end of the tub-

ing into substantially the box form of the bag bottom, means to retract the grippers from the tubing as they release it, a curved plate and a flattening means rigidly supported in the line of travel of the tubing 70 and acting to fold the partly formed bag bottom into the diamond fold and against the body of the tube, and means to draw the bag blank away from the grippers and against the plate and flattener. 75

15. In a paper bag machine a plate suitably supported and curved near its free end, a stiffening rib and a flattener supported by said rib, and made integral with said rib and plate, and means to draw a partly formed bag bottom against and around said plate and past said flattener by which it is folded into the diamond form. 80

16. In a paper bag machine, a curved plate and stiffening rib, and a flattening means supported by said rib all made integral, said plate being adapted to clear the inner creases of the side tucks of the tubing and said plate being rigidly supported in the line of travel of the tubing 85 substantially as specified. 90

17. In a paper bag machine, mechanism for spreading the diamond fold on the end of tucked tubing comprising a pair of non-contacting rolls between which the tubing 95 passes in combination with four side grippers arranged in pairs at each end of the rolls and rotating therewith, bearing faces upon the outer ends of said grippers, the grippers of each pair being adapted and so arranged that while rotating, they coöperate with each other by the contact of their bearing faces and act to grip the tubing to the rolls and form the corners and side edges of the bag bottom, a blade carried by one of the rolls to form the cross-line P¹² in one face only of the tubing, a curved plate and a flattening means rigidly supported in the line of travel of the tubing and acting to fold the partly formed bag bottom into the diamond fold and against the body of the tube, and means to draw the bag blank away from the grippers and against the plate and flattener. 100 105

18. In a paper bag machine, the combination of rolls as 67 and 68 carrying a tube-cutting mechanism and between which the tubing passes, one of said rolls carrying a blade by which the line P¹² is defined in one face only of the tubing, four rotating side 115 grippers supported in pairs at each end of said rolls, coöoperating bearing faces upon the grippers adapted to come in contact whereby the grippers operate to form the corners and side edges of the bag bottom, a 120 plate and a flattener made integral and rigidly supported, and arranged to fold partly formed bag bottoms into diamond form, and means to draw the bag blank away from the grippers and against the plate and flattener. 125 130

19. In a paper bag machine, creasing plates adapted to project within the tucks of the tubing and separate the tucks, a creasing groove in one face of the creasing plates, a creasing groove in the opposite face of the creasing plates, means to operate with the creasing plates to crease the faces of the tubing and its tucks, and means to support and operate the plates and the creasing means.
20. In a paper bag machine, creasing plates adapted to project within the tucks of the tubing, rotating creasing blades arranged to operate with the creasing plates and crease one face of the tubing and one-half of the tucks in one direction, and to crease the opposite face of the tubing and its half of the tucks in the opposite direction, and mechanism to support and to operate the plates and blades.
21. In a paper bag machine, the combination of means for creasing the opposite faces of the tubing and its tucks in opposite directions toward each other, a pair of rolls between which the tubing passes, rotating side grippers as 88, 88, 88, 88, arranged to swing their gripping ends between the rolls and into the tucks of the tubing, and grip the tubing to the faces of the rolls and form the corners and side edges of the bag bottom to be formed, where the faces of the tubing and tucks have been creased.
22. In a paper bag machine, the combination of mechanism for creasing the opposite faces of the tubing and its tucks in opposite directions toward each other, a pair of rolls between which the tubing passes, rotating side grippers as 88, 88, 88, 88, arranged to swing their gripping ends between the rolls and into the tucks of the tubing, and grip the tubing to the faces of the rolls and form the corners and side edges of the bag bottom to be formed, where the faces of the tubing and tucks have been creased, and a plate and its flattener arranged to fold the partly formed bag bottom into the diamond form and against the body of the tubing.
23. In a paper bag machine, the sleeve extensions 44, 44, collars 45, 45, having extensions 46, 46, and 46^a, 46^a, angles 47, 47, secured to faces 46^b, 46^b, the slideways in which are supported the angular creasing plates, rolls 51^c, 51^c, levers 53, 53', secured to shaft 52, cam roll 53^b bearing against cam 56 secured to shaft 38, the spring 57, the creasing hubs 39, 39, 39, 39, and the creasing blades 61, all supported and arranged to operate substantially as and for the purpose specified.
24. In a paper bag machine, the combination of a suitable base, a bracket secured to the base at one side of the machine center, said bracket consisting of an upright portion having at its upper end an overhanging
- extension toward and near to the center of the machine, a tab cutting and creasing means supported at the end of said extension, and mechanism supported by said bracket acting to operate said cutting and creasing means, substantially as shown and described.
25. In a paper bag machine, the combination of a suitable base, a bracket secured to the base at one side of the machine center, said bracket consisting of an upright portion having at its upper end an overhanging extension toward and near to the center of the machine, a former post secured to said base, a former plate supported by said post, roll 10 provided with grooves and block 16 between which the paper passes, knife 18 adapted to pass its teeth through the paper and into said grooves, thereby cutting a complete tab at one operation, and mechanism supported by said bracket and said post to operate the tab cutting means, substantially as shown and described.
26. In a paper bag machine, a tab cutting and creasing mechanism consisting of roll 10 provided with grooves, and block 16 between which the paper passes in combination with knife 18 adapted to pass its teeth through the paper and into the grooves thereby cutting a complete tab at one operation, blade 19 and edge 15 to crease the tab and cause it to stand at an angle with the paper as it is drawn into the machine and means to support and operate the tab cutting and creasing mechanism substantially as shown and described.
27. In a paper bag machine, mechanism for cutting a tab in the paper and causing the tab to stand at an angle with the paper in combination with a pair of rolls between which the tubing passes, one of said rolls having a clearance space formed in one side of it into which the said tab projects as it approaches the roll, thereby permitting the tube cutting mechanism to cut the tube without mutilating the tab, said tube cutting mechanism and rotating side grippers as 88, 88, 88, 88, arranged to operate with each other in pairs and with the said rolls and tubing, substantially as specified.
28. The combination in a paper bag machine with means for forming bellows folded tubing and for preparing the forward end of such tubing for the formation of a diamond fold, of mechanism for spreading the diamond fold, comprising suitable rolls side grippers arranged in pairs rotating with rolls and provided with gripping ends entering the tucks and gripping them to the rolls, and also spreading the folds and forming the side edges and corners of the bottom, said grippers being caused to thus act by their contact with each other, and mechanism for flattening the bottom.
29. A paper bag machine having means

- against which to grip tucked tubing in combination with suitably supported and rotating side grippers adapted and so arranged that while rotating and contacting with each other they themselves project their gripping means between the tucks of the tubing and grip the tubing to said first mentioned means and form the corners and side edges of a bag bottom.
- 10 30. A paper bag machine having a knife adapted to cut through all the plies of the tucked tubing and leave an uncut connection as p^{10} between the bag lengths, a gripping means upon the rolls located forward of the knife and acting to put tension on the paper in combination with non-contacting rolls between which the tubing passes and by which the knife and gripping means are carried.
- 15 31. In a paper bag machine, the combination with two non-contacting rolls 67 and 68 between which the tucked tubing passes self-actuating side grippers 88 mounted to rotate with said rolls and having gripping ends whereby they grip the tubing to the rolls, cutting means for cutting through all the plies of the tubing, except an uncut connection between the bag lengths, and gripping means also mounted on the rolls located forward of the cutting knife and acting to put tension on the paper.
- 20 32. In a paper bag machine, the combination with two non-contacting rolls 67 and 68 between which the tucked tubing passes, self-actuating side grippers 88 mounted to
- rotate with said rolls and having gripping ends whereby they grip the tubing to the rolls, cutting means for cutting through all the plies of the tubing, except an uncut connection between the bag lengths, a bending blade, as 100, also carried by one of said rolls, and gripping means also mounted on the rolls located forward of the cutting knife and acting to put tension on the paper.
- 25 33. In a paper bag machine, means against which to grip tucked tubing in combination with suitably supported and rotating side grippers adapted and so arranged that while rotating and contacting with each other, they project their gripping means between the tucks of the tubing and grip the tubing to the said first mentioned means, said projecting and gripping action of the side grippers being caused by no other means than themselves.
- 30 34. In a paper bag machine, means for preparing the end of the tucked tubing for the formation of a diamond fold, comprising means for feeding the tubing, means for forming a tab in the paper, means for creasing said tab so that it will stand at an angle to the tubing and enable it to clear the cutting means by which the tubing is severed, means for severing the tubing, and means for spreading open the bottom.
